STOKER

Joseph S. Bennett, Merion, Pa., assignor to American Engineering Company, Philadelphia, Pa., a corporation of Pennsylvania

Original application May 13, 1937, Serial No. 142,389. Divided and this application September 29, 1939, Serial No. 297,068

3 Claims. (Cl. 110—44)

This application is a division of my co-pending application Ser. No. 142,389, filed May 13, 1937, patented on April 2, 1940, under No. 2,195,808, and relates to furnace stokers, and more particularly to the overfeed section or extension grates of such devices.

One object of the present invention is to provide a generally improved extension grate construction which functions to both agitate and feed the partially consumed fuel and refuse toward the dump plates or ash pit of the furnace.

Another object is to provide an extension grate consisting of vertically and horizontally movable elements for agitating and feeding the partially consumed fuel and refuse toward the ash pocket or dump plates of the furnace.

Another object is to provide an extension grate of the stated character adapted for use in connection with fluid cooled stokers.

Other and more specific objects will become apparent as the description of the invention progresses.

Of the drawings:

Fig. 1 is a longitudinal sectional view taken through one of the retorts of an underfeed stoker showing the invention applied to a stoker of the fluid cooled type.

Fig. 2 is an enlarged sectional view taken through the extension grate.

Fig. 3 is a plan view partly in section, of the construction shown in Fig. 2, with some of the parts removed to show the construction thereof.

Fig. 4 is a view taken substantially along line 4—4 of Fig. 3.

Fig. 5 is a longitudinal sectional view taken through an extension grate of a modified construction.

Fig. 6 is a plan view partly in section of the extension grate shown in Fig. 5, with parts broken away and others removed to show the construction thereof.

Fig. 7 is a plan view of the framework of an extension grate section of the type shown in Figs. 5 and 6, and

Fig. 8 is a side elevational view partly in section, taken substantially along line 8—8 of Fig. 7.

Fig. 9 is a side view of a bearing bracket.

Referring to the drawings, the numeral 1 designates generally a stoker consisting in the present instance of alternately disposed retorts 2 and tuyère rows 3. Fuel from a hopper 4 is fed to the retorts 2 by rams 5, driven by any suitable power mechanism indicated generally at 6. The bottom of each retort 2 consists of a series of alternately disposed pushers 7 and dead plates 8, the pushers 7 being reciprocated by the power mechanism 6 through any suitable link and lever mechanism indicated generally at 9. The lower end of each retort is provided with an extended dead plate or coal plate 10. A series of overfeed

or extension grate sections 90 provided at the lower end of the stoker feed the partially consumed fuel and refuse to dump plates 12 which in turn may be actuated from time to time by any suitable operating mechanism to discharge the refuse accumulating thereon into an ash pocket 13. The extension grate sections 90 may also be actuated by the power mechanism 6 through any suitable link and lever mechanism indicated generally at 14. For a more detailed description of the operating means for the rams, pushers and extension grates reference may be had to United States Patent No. 2,005,005.

Draft air is supplied to the furnace from a plenum chamber 15 which receives its air from any suitable fan or blower mechanism (not shown) through a communicating passage 16. Air is supplied to the extension grate sections 90 from a common chamber 17 disposed therebeneath which communicates with chamber 15 by means of a communicating passage 18 having an adjustable damper 19 provided therein.

Mounted in cooling relation with each tuyère row 3, and a portion of the front wall 20 of the furnace, are fluid conducting tubes 94. These tubes extend downwardly and form a portion of the overfeed section 90, and terminate at their lower ends in a transversely disposed header 22. The upper ends of tubes 94 are connected to one of the steam drums of a boiler (not shown). Also mounted in cooling relation with each coal or dead plate 10 are tubes 95. The rearwardly disposed ends of these tubes extend in parallel relation with the lower ends of tubes 94, and also terminate in header 22. The forwardly disposed ends of tubes 95 terminate in a transverse header 24 mounted in any suitable manner beneath the stoker 1. Fluid from the boiler is supplied to header 22 by downtake connections 25, while uptake connections 26 connect header 24 with the boiler after a well known fashion.

The term "front" herein employed in the description of the various elements indicates the portion of the elements extending toward the front or power mechanism 6 of the stoker, while the term "rear" indicates the portions extending toward the rear or dump plates 12.

Each extension grate unit 90 consists of a series of rocking or vertically movable elements 91, and a corresponding series of reciprocating elements 92, mounted on a stationary framework 93.

Secured by bolts 99, depending from tubes 94 and 95, are plates 100. These plates are provided with upper and lower slots 101 and 102 respectively, for receiving elements 91 and 92, and have a series of apertures 100' through which draft air may pass. Each element 91 is also of angular construction, and comprises a relatively narrow fuel engaging portion 103, and has de-

pending from the front end thereof a bifurcated arm 104. As shown more particularly in Figs. 3 and 4, each extension grate section 90 in the present instance consists of five sets of elements 91 and 92, although the number of such elements may be either increased or decreased without departing from the invention. Elements 91 are pivotally supported upon a rod 105 mounted in a pair of rearwardly extending brackets 106, secured by bolts 107 or any other suitable fastening means to the front closing plate 108. The reciprocatory elements 92 are of substantially rectangular construction, each having a rounded nose or fuel engaging portion 109. The lower edge 110 of each element 92 rests upon the flat surface 111 at the lower end of slot 102, as shown in Fig. 2. Elements 92 are also supported on bearing blocks 112 secured at the rearwardly disposed sides of tubes 94 and 95. The upper surfaces 113 of blocks 112 form a continuation of surfaces 111, whereby extended bearing surfaces are provided for elements 92. The lower ends of bifurcated arms 104 of elements 91 are each provided with a pair of aligned slots 114 through which extends an operating rod 115. As shown in Figs. 3 and 4, operating rod 115 also extends through apertures provided near the forwardly disposed ends of reciprocatory members 92. Rod 115 has secured thereto a yoke 116 to which is secured an operating rod 117. Rod 117 operates in any suitable bearing 118 provided in front closing plate 108, and may be operatively connected to any suitable power mechanism, such as that shown in Fig. 1. It therefore is seen that upon actuation of rod 117 and yoke 116, the elements 91 of each section will be rocked about their pivots 105, and at the same time each of the elements 92 will be moved longitudinally. By this construction also, any masses of fuel or clinker supported on the overfeed section will be broken up by the action of elements 91, and at the same time urged downwardly. The fuel and refuse will then be engaged by reciprocatory elements 92 and moved to any suitable refuse receiving device, such as to the dump plates 12 pivotally supported at the rear of the stoker.

Figs. 5 to 8 illustrate a further embodiment of the present invention. In this construction no fluid conducting tubes are employed with the underfeed or overfeed sections thereof. As shown more particularly in Figs. 5 and 6, this construction, like that shown in Figs. 2 to 4, comprises a series of rocking extension grate elements 125, and a corresponding series of reciprocatory elements 126 mounted on any suitable framework 127. Framework 127 comprises a pair of substantially triangular side plates 128 and 129, which are connected at the upper ends thereof by a cross member 130, and at their lower edges by a pair of spaced cross members 131 and 132. Secured to and extending upwardly from cross members 131 and 132 are a series of guide plates 133. The side plates 128 and 129 of each extension grate frame 127 have extending inwardly from the forwardly disposed edges thereof flanges 134, each having a pair of apertures provided therein. Flanges 134 are secured to the front closing plate 135 of the overfeed section in any suitable manner, such as by bolts 136. The inclined edges 137 of side plates 128 and 129 are provided with a downwardly and forwardly inclined bearing slot 138 for receiving the rounded ends 139, 140 of a square shaft 140 upon which the front ends of rocking elements 125 are supported. Also mounted at the ends of the square

portion of shaft 140 is an operating member 141. This member consists of a pair of arms 142 and 143 terminating at the forwardly disposed ends thereof in hub portions 144, each having a square aperture provided therein for receiving shaft 140. The rearwardly disposed ends of arms 142 and 143 are integrally connected to a transverse, substantially angular plate or bail member 145 upon which the rearwardly disposed ends of elements 125 are supported. Each of the elements 125 has provided at the forwardly disposed end thereof a hub portion 146 having an open slot 147 provided therein which is adapted to engage the square portion of shaft 140, as shown in Fig. 5. The rearwardly disposed ends of elements 125 are secured to bail 145 in any suitable manner, such as by stud bolts 148. Extending rearwardly from elements 125 of each extension grate section are a pair of stationary plates 149. These plates are provided with a pair of downwardly extending apertured ears 150. Plates 149 rest upon the upper edges of vertical plates 133, and also upon the lower portion of the inclined edges 137 of side plates 128 and 129, as shown in Figs. 5 and 6, and the apertured ears 150 thereof are secured to certain of the vertical plates 133 in any suitable manner, such as by bolts 151, as shown in Fig. 5.

Elements 126 are of substantially rectangular construction, having upper and lower, substantially parallel edges 152 and 153, which terminate at the rearwardly disposed ends thereof in a rounded nose or fuel engaging portion 154. The forwardly disposed end of each element 126 is provided with an irregular-shaped slot 155, which is open at the forward end thereof, as shown in Fig. 5. The lower edge 153 of each element 126 is supported upon cross members 131 and 132, and is guided for operation between a pair of plates 133, or between a plate 133 and one of the side plates 128 or 129, as the case may be. Operating member 141 has depending from the hub portion of each of the arms 142 and 143 thereof a second arm 156. Arms 156 are each provided with a substantially vertical slot 157 near the lower end thereof for receiving certain elements of an operating mechanism 158, secured to a reciprocating rod 159 mounted in a bearing provided in the front closing plate 135. Operating member 158 consists of two spaced, rearwardly extending arms 160 and 161, each of which having an aperture 162 therein disposed in registering relation with the vertical slots 157 of arms 156. A pair of pins 163 and 164 extending through these apertures 162 and slots 157 operatively connect member 141 with the operating mechanism 158. Thus, upon actuation of operating mechanism 158 a rocking movement will be imparted to member 141, and consequently to elements 125.

The rearwardly disposed ends of arms 160 and 161 are also provided with apertures through which extends an operating rod 165. The right hand end of this rod extends through an elongated slot 167 provided in side plate 129, as shown at 168. Rod 165 also extends through the slots 155 provided in elements 126 and actuates the latter upon operation of member 158. In order to install the elements 126 on an extension grate unit, each element is simply moved forwardly in such a manner that the open end of slot 155 is inserted on rod 165, and then lowered until it assumes the position shown in Fig. 5. As therein shown, a downwardly extending projection 169 is provided at the for-

ward end of each element 126 which acts as an abutment to enable the operating rod 165 to actuate the elements forwardly after a feeding operation. In order to vary the extent of movement of each of the elements 126 an adjustable bolt 170 is provided in projection 169. By adjusting this bolt the lost motion provided by the extended portion 171 of slot 155 may be varied.

Referring to Fig. 6, it will be observed that the end elements 125' of each of the extension grate units are somewhat wider than the intermediate elements 125 so as to extend over the top and beyond the outer extremities of side plates 128 or 129. These extended portions of adjacent elements 125', thereby occupy the space between adjacent units. It will also be observed that the stationary elements 149, 149 of each unit also extend beyond the side plates 128 and 129 of the framework and form an extension of element 125'. In order to prevent dead spaces between the lower ends of adjacent grate units, an additional reciprocating element 126' is mounted for movement between side plates 128, 129 of the adjacent units. The rearwardly disposed ends of reciprocating elements 126' rest upon pairs of bearing extensions 172, 172 extending outwardly from the lower edges of side plates 128 and 129. The forward end of each element 126' is also provided with an irregularly-shaped slot 155' similar to the slot 155 provided in elements 126. This slot receives the extended portion 168 of a corresponding operating rod 165. Also extending between the side plates of adjacent extension grate units is a bearing bracket 173 having an open bearing slot 174 provided at the rearwardly disposed end thereof which receives the rounded end portions of shafts 140. These brackets 173 thus afford additional bearings for these shafts.

From the foregoing description it is apparent that the various elements of the extension grate units may be readily installed upon the framework, or in case damage should occur thereto during operation of the stoker, they may be readily renewed. To renew one of the elements 125 or 125' it is only necessary to remove bolt 148, and then lift the element from engagement with the square portion of shaft 140. A new element may then be readily inserted in position and secured to the bail 145. To renew an element 126 it is only necessary to tilt the same until shaft 165 lies in the lower portion 178 of slot 155, and to then move element 126 rearwardly to clear the shaft. To replace such an element with a new one the process is reversed. The element is actuated so that the lower portion 178 of slot 155 engages shaft 165 and clears the downwardly extending projection 165. The element is then lowered until it occupies the position shown in Fig. 5. To renew one of the elements 149 it is only necessary to remove bolts 151 when the same may be lifted from the framework. Also by removing operating pins 163 and 164 the member 141, and all of the elements 125 and 125' supported thereon, may be lifted out of the bearings provided in side plates 128 and 129, and brackets 173.

In operation draft air may pass to the fuel bed between elements 125 and 125', and also between the elements 126 and 126', as well as between stationary elements 149. However, in order to allow a greater quantity of air to flow into the fuel bed, apertures 175 and 176 may be provided in

the elements 125, 125' and elements 149 respectively.

From the foregoing description it is seen that the various embodiments of the invention herein shown are extremely effective in agitating the fuel, thereby breaking up clinker and masses of fuel and feeding the same to dump plates provided at the rear of the stoker. By this construction efficient combustion of the fuel is effected, as well as the elimination of large clinker masses, which often occur during operation of the furnace.

While the various embodiments herein shown and described are admirably adapted to fulfill the objects primarily stated, it is to be understood that the invention is not to be limited thereto since it may be embodied in other forms, all coming within the scope of the claims which follow.

20 What is claimed is:

1. An extension grate for stoker furnaces, comprising a stationary framework, a transverse member supported in said framework, an upper series of rocking grate elements detachably supported on said member, an operating member for said rocking elements, means for detachably securing said elements to said operating member, actuating means for said member, a lower series of reciprocatory grate elements mounted in said framework, means for detachably securing said last mentioned elements to said actuating means, and adjustable means between said reciprocatory elements and said actuating means whereby the extent of movement of said reciprocatory elements may be varied.

2. An overfeed section for stoker furnaces, consisting of a plurality of extension units arranged in side by side relation, each of said units comprising a framework, a series of rocking grate elements supported in said framework, a corresponding series of reciprocating elements also mounted in said framework, stationary grate elements disposed between said rocking and reciprocating elements, certain of said rocking and stationary grate elements extending beyond the outer extremities of the associated framework, an operating member for actuating said rocking and reciprocating elements, a rod connecting said reciprocating elements to said operating member.

40 3. An extension grate for stoker furnaces, consisting of a plurality of extension units arranged in side by side relation, each of said units comprising a framework, a series of rocking grate elements supported in said framework, a corresponding series of reciprocating elements also mounted in said framework, stationary grate elements disposed between said rocking and reciprocating elements, certain of said rocking and stationary grate elements extending beyond the outer extremities of the associated framework, an operating member for actuating said rocking and reciprocating elements, a rod connecting said reciprocating elements to said operating member, one end of said rod extending laterally from said framework, and an additional reciprocating element disposed between the frameworks of adjacent units and operatively connected to the extended portion of said rod whereby said last mentioned reciprocating element moves in unison with the reciprocating elements of the associated extension grate unit.

45 4. An extension grate for stoker furnaces, comprising a stationary framework, a transverse member supported in said framework, an upper series of substantially L-shaped rocking grate elements supported on said member, one portion of each of said grate elements constituting the fuel supporting portion thereof, while the other portion thereof constituting an operating element, an operating member operatively attached to said last mentioned portion of said elements, a lower series of reciprocatory grate elements mounted in said framework, means for attaching said reciprocatory elements to said operating member, and stationary grate elements disposed between said rocking and reciprocatory grate elements.

50 JOSEPH S. BENNETT.
